GEORGE W. S. BELL.

By Atty. N. Dubois,

UNITED STATES PATENT OFFICE.

GEORGE W. S. BELL, OF TALLULA, ILLINOIS, ASSIGNOR TO BELL & DAWSON,
OF SAME PLACE.

FENCE-MACHINE.

SPECIFICATION forming part of Letters Patent No. 660,267, dated October 23, 1900.

Application filed February 16, 1900. Serial No. 5,500. (No model.)

To all whom it may concern:

Be it known that I, GEORGE W. S. BELL, a citizen of the United States, residing at Tallula, in the county of Menard and State of Illinois, have invented certain new and useful Improvements in Fence-Machines, of which the following is such a full, clear, and exact description as will enable others skilled in the art to which it appertains to make and use my said invention.

My invention relates to fence-machines of that class which are employed to interweave with the horizontal strands of a fence vertical stay-wires placed at suitable distances apart to strengthen the fence and prevent displacement of the horizontal strands thereof.

In general terms my invention embraces a main structure or frame maintained in a vertical position with respect to the horizontal strands of the fence, movable in the longitudinal direction of the fence, and carrying twisting mechanism slideable vertically on said frame and adjustable relative to the horizontal strands of the fence.

The purposes of my invention are to provide a main frame so constructed and arranged that the frame may slide on the horizontal strands of the fence, to provide simple and effective means to support the weight

of the machine so as to maintain substantial parallelism of the longitudinal strands of the fence and prevent sagging thereof during the operation of twisting the vertical stay-wires, to provide effective means to prevent accidental transverse displacement of the longitudinal strands of the fence, to provide means for securing the frame in any desired position on the longitudinal strands of the fence, to provide means to facilitate the placing of the

frame on the longitudinal fence-wires and its removal therefrom, to provide means for holding one end of the vertical stay-wire while the twist is being made, to provide a twister-frame of novel and improved form, to provide twisting mechanism of novel and improved construction, to provide a novel and improved means for supplying wire to the twister, and to provide simple and effective means for limiting the rotation of the twister.

With these ends in view my invention consists of the novel features of construction and combinations of parts shown in the annexed

drawings, to which reference is hereby made, and hereinafter particularly described, and pointed out in the claims.

Referring to the drawings, Figure 1 is a perspective view of the complete machine. Fig. 2 is an enlarged top plan view of the twister-frame and the twisting mechanism supported thereon. Fig. 3 is a vertical longitudinal section through the twister mechanism on the line 3 3 of Fig. 2. Fig. 4 is an enlarged vertical transverse section on the line 4 4 of Fig. 2. Fig. 5 is an enlarged horizontal transverse section through the main frame and connected parts on the line 5 5 of Fig. 1. Fig. 6 is an enlarged detached perspective view of a part of one side rail and shows the lever which operates the clamping-slide in position on the side rail. The clamping-slide is omitted from this view in order to more clearly show the underlying parts. Fig. 7 is an enlarged perspective view of part of the clamping device near the lower end of one of the side pieces, which serves to retain the machine in place on the longitudinal wires of the fence. Fig. 8 is an enlarged vertical section through the spool-frame and spool on the line 8 8 of Fig. 4.

Similar letters of reference designate like parts in all of the views.

The main frame is rectangular in form and consists of side pieces A, united near their extremities by cross-pieces A'. The side pieces A are of rectangular cross-section and have in their fronts transverse notches a. The notches a correspond in number and position to the number and position of the longitudinal strands of wire in the fence, and when the machine is in position on the fence a single strand of wire lies in each pair of notches, as clearly shown in the drawings.

In one of the side pieces A is a longitudinal channel a', in which the web of the T-bar A² fits loosely. A bolt a² passes transversely through the side piece A and the bar A², and the bar turns on the bolt. Transverse notches in the web of the bar A² register with the transverse notches in the side piece A. A bolt a³, near the lower extremity of the bar A², passes through the bar and through the side piece A and serves to secure the bar in the position shown in Fig. 1. When the bar A² is secured in the position above described, it

prevents accidental withdrawal of the longitudinal wires of the fence from the transverse notches in the side pieces A. When it is desired to move the machine from the longitudinal wires of the fence, the bolt a^3 is withdrawn and the bar A² is turned on the bolt a^2 to withdraw the web of the bar from the channel a' , thereby leaving the notches a unobstructed, so that the wires may be easily withdrawn from the notches.

Brackets B are secured to one of the side pieces A. A gas-pipe B' passes through holes in the brackets B and is detachably connected with one of the brackets by a bolt b , passing transversely through the bracket and through the gas-pipe. The pipe B' may be disconnected from the frame by removing the bolt b and withdrawing the pipe from the brackets B.

Box-shaped guides D are secured at suitable distances apart on one of the side rails A, and the clamp-slide D' is slideable in the guides. A lever D² has its fulcrum d on a link D³, which has a pivotal connection d' with the side piece A. One end of the lever D² has a pivotal connection d^2 with the slide D'. In one edge of the slide D' are transverse notches d^3 , spaced to register with the transverse notches a in the side piece A. The notches a and d^3 are alike, except that the notches a are longer than the notches d^3 . A plate D⁴, having at its lower end a transverse notch d^4 , is secured to the side piece A by rivets or other suitable means contiguous to the uppermost notch a . A plate D⁵ is secured to the slide D', contiguous to the uppermost notch d^3 , and the upper end of the plate enters the notch d^4 in the plate D⁴. The plate D⁵ is drawn toward the plate D⁴ by pushing the free end of the lever D² downward and is moved away from the plate D⁴ by pulling the lever D² upward.

Guard-plates A³, having downwardly-extending fingers a^4 , are suitably secured to the side piece A in such position that the fingers a^4 extend nearly the full length of the notches, as clearly shown in Figs. 1 and 7. Each of the notches a on that side piece on which the slide D' is mounted, except the uppermost notch, is provided with a guide-plate A³. The fingers a^4 serve to prevent lateral displacement of the longitudinal fence-wires, which lie in the notches a and d^3 , when the main frame is in position on said fence-wires.

In placing the main frame on the longitudinal fence-wires the lever D² is raised, so as to move the slide D' downward to such extent as to bring the notches d^3 in registry with that part of the notches a which is under the lower extremity of the finger a^4 . The wires are then placed in both notches, and the lever D² is pushed downward, so as to move the slide D' upward and cause the slide to draw the wires upward in the notches a under the guard-plates A³ and cramp them in the angle of the plates, thereby securing the frame so as to prevent longitudinal move-

ment of the frame on the wires. For greater security against longitudinal movement of the frame on the fence-wires I provide one of the notches a , near the lower extremity of the side piece A, with a crimping-plate A⁴, secured to the side piece A opposite to the plate A³ in such position that the lower edge of the plate A⁴ extends somewhat below the upper end of the notch a , and when the frame is in position on the wire the plate A⁴ crimps that part of the wire on which it rests to such extent as to prevent the plate from slipping on the wire.

The twister mechanism is carried on an arch-shaped frame E, having a handle E', which may be grasped by the operator to support the outer end of the frame. A tubular sleeve E² is provided with a trunnion e , mounted to turn in suitable bearings on brackets e' on the frame E. The sleeve E² fits around and is slideable on the pipe B'. A brace-handle E³ has at one extremity a stud-pin e^2 , which turns in a suitable hole e^3 in the end 90 of the handle E'. The other extremity of the brace-handle is secured to a shaft E⁴, which turns in bearings e^4 on the frame E. A tubular shaft E⁵ turns in a suitable bearing in an extension e^5 of the frame E. Parallel jaws e^6 project laterally from the extension e^5 in a line parallel to a continuation of the axial line of the shaft E⁴. A cog-wheel E⁶ is secured to one extremity of the shaft E⁵, and a collar E⁷, secured at the other extremity of said shaft, serves to prevent longitudinal movement of the shaft in its bearing. The shaft E⁵ has a longitudinal slit e^7 , which registers with the opening between the jaws e^6 when the moving parts of the twister occupy 105 the relative positions shown in Figs. 2, 3, and 4. A cog-wheel E⁸ is secured to and turns with the shaft E⁴ and meshes with and drives the cog-wheel E⁶. A notched wheel E⁹ turns on a pin e^9 on a standard e^8 on the frame E. On the wheel E⁹ are oppositely-extending lugs 110 e^{10} , with which a finger e^{11} on the brace-handle E³ engages to limit the rotation of the brace-handle, as hereinafter explained. A toothed wheel E¹², secured on the shaft E⁴, 115 engages with and drives the notched wheel E⁹. The wheel E⁹ has six equidistant notches so placed that each revolution of the toothed wheel will cause the notched wheel to make one-sixth of a revolution. Hence three complete revolutions of the toothed wheel will move the notched wheel one-half of a revolution.

Starting with the parts of the mechanism in the relative positions shown in Figs. 2, 3, 125 and 4, if the brace-handle E³ be turned three times around in the direction indicated by the arrow X the finger e^{11} will at the end of the third revolution strike against that lug e^{10} which in the drawings, Fig. 4, appears as the lower lug and will stop further rotation of the brace-handle in that direction, and the brace-handle may then be turned three times around in the opposite direction, again stop-

ping with the parts in the positions shown in Fig. 4. It will be seen, then, that by employing the means described uniform triple rotations alternately to the right and to the left 5 may be imparted to the wheel E⁶ and that the wheel cannot make more than three turns in either direction. Each triple revolution of the wheel E⁶ produces three turns of the stay-wire around the longitudinal strand of the 10 fence, and since the revolutions of the brace-handle are automatically limited to triple turns to the right and left alternately uniform windings of the three turns each of the stay-wire around the longitudinal wires of the 15 fence may be made without special care or watchfulness on the part of the operator, thus enabling an unskilled operator to produce fence of superior quality. In order to place the twisting device on the longitudinal 20 fence-wires in position to twist the stay-wires thereon, the slot e⁷ in the shaft E⁵ must be in registry with the opening between the forks e⁸, and this occurs only when the finger e¹¹ is 25 against or contiguous to one of the lugs e¹⁰. In the practical use of the machine the striking of the finger e¹¹ against the lugs e¹⁰ apprises the operator that three complete turns have been made and that the slot e⁷ is in juxtaposition to the fork e⁸ and that the twister 30 may be moved into position to twist the next stay-wire.

A spool-holder frame E¹³ on the wheel E⁶ is preferably integral therewith. The spool E¹⁴ is tubular and has at one end a spindle e¹², 35 which turns in suitable bearings in the frame E¹³. A spring e¹³ fits in the bore of the spool. A pin e¹⁴ is slidable in the bore of the spool, and the spring e¹³ acts against the lower end of the pin to keep it in its bearing in the frame 40 E¹³. When it is desired to remove the spool, it is only necessary to push the pin e¹⁴ downward to withdraw it from its bearing in the frame E¹³ when the spool may be easily removed.

Having fully described my invention, what I claim as new, and desire to secure by Letters Patent, is—

1. In a fence-machine, the combination of a main frame having transversely-notched 50 side pieces, one of said side pieces having a longitudinal channel, and a notched T-bar pivotally connected with said last-named side piece and fitting in the channel therein, as set forth.

2. In a fence-machine, the combination of a main frame having transversely-notched side pieces, guides secured to one of said side pieces, guard-plates secured to said last-named side piece contiguous to the notches 60 therein, a notched slide slidable in said guides, and means for reciprocating said slide, as set forth.

3. In a fence-machine, the combination of a main frame having transversely-notched 65 side pieces, guard-plates on one of said side

pieces, a slide slidable on said last-named side piece and having notches contiguous to said guard-plates, and a longitudinal bar having a hinge connection with one of said side pieces, as set forth. 70

4. In a fence-machine, the combination of a main frame, a longitudinal bar detachably connected with the main frame, and a twister-frame slidable on said bar, as set forth. 75

5. In a fence-machine, the combination of an arch-shaped twister-frame having a projecting handle, a brace-handle mounted to turn within the arch of said twister-frame, and twisting devices operated by said brace-handle, as set forth. 80

6. In a fence-machine, the combination of a twister-frame, a brace-handle mounted to turn on said twister-frame and provided with a stop, a toothed wheel turning with said brace-handle, twisting mechanism actuated 85 by said brace-handle, and a notched wheel intermeshing with said toothed wheel and provided with lugs adapted to engage with the stop on said brace-handle, as set forth.

7. In a fence-machine, the combination of a twister-frame, a rotatable brace-handle provided with a stop, a toothed wheel and a cog-wheel turning with said brace-handle, jaws on the twister-frame, a slotted tubular shaft turning in a bearing on the twister-frame, a 95 cog-pinion on said tubular shaft intermeshing with the cog-wheel on the brace-handle, and a rotatable notched wheel meshing with said toothed wheel and having lugs adapted to engage with a stop on the brace-handle, as 100 set forth.

8. In a fence-machine, a spool having a tubular stem, a spring housed in said spool, and a pin slidable in said spool, in combination with a twisting mechanism in coöperative relation to said spool, as set forth. 105

9. In a fence-machine, the combination of a main frame, a guard-plate and a crimping-plate on said frame, and a notched slide slidable on the main frame in juxtaposition to 110 said guard-plate, as set forth.

10. In a fence-machine, the combination of a notched side piece, a clamp-plate secured to said side piece contiguous to the notches therein, and a notched slide slidable on said 115 side piece and coöperative with the clamp-plate thereon, as set forth.

11. In a fence-machine, the combination of a notched side piece, a link pivotally connected with said side piece, a lever pivotally connected with said link, and a notched slide 120 pivotally connected with said lever, as set forth.

In witness whereof I have hereunto subscribed my name, at Tallula, Illinois, this 9th 125 day of November, 1899.

GEORGE W. S. BELL.
